UNITED STATES PATENT OFFICE.

OTTO ARMLEDER, OF WYOMING, OHIO.

SELF-PROPELLED VEHICLE.

1,351,199.

Specification of Letters Patent. Patented Aug. 31, 1920.

Application filed April 28, 1919. Serial No. 293,170.

To all whom it may concern:

Be it known that I, OTTO ARMLEDER, a citizen of the United States, residing at Wyoming, in the county of Hamilton and State of Ohio, have invented certain new and useful Improvements in Self-Propelled Vehicles, of which the following is a specification.

In self-propelled vehicles, including trucks, 10 the chassis is formed as a rigid built-up structure, built up, for instance out of I-beams, suitably rigidly connected at the corners of the chassis. In actual practice the chassis, regardless of how the same may 15 be constructed, is subject to strains, and actual relative movements between its parts usually take place. For instance, there may be a torsional movement in the structure, occasioned by one wheel striking a boulder 20 or being let into a rut, whereby one corner of the chassis is subjected to severe strains, which result in movement of that corner up or down with relation to the balance of the chassis. The chassis is also frequently subjected 25 to longitudinal strains in reverse directions at its respective sides, producing hinge-like strains on and movements at the corners of the chassis and movements in reverse directions of the sides. Other strains 30 and movements are also caused. These strains and vibrations are rapidly recurrent.

It has been the usual practice heretofore to rigidly connect the motor-frame and the chassis, for instance by means of bolts passing 35 through the I-beams of the chassis directly into the metal of the casing of the motor, for rigidly securing the two together. In such a structure the strains and movements in the chassis are communicated directly 40 to the motor, resulting in detrimental strains in the motor and frequently in breakages of the motor-frame or parts.

It is the object of my invention to avoid these objections, and, furthermore, to provide 45 supporting means for a motor on the chassis arranged to compensate for the strains and movements to which the chassis is subjected; further, to provide a comparatively stiff bent leaf-spring having its edges 50 presented up and down, between the chassis and the motor-frame, preferably at each side of one end of the motor-frame; further, to provide such suspension in connection with a pivot-suspension at the other 55 end of the motor-frame; and, further, to provide novel means whereby a resiliently

yieldable connection between the motor-frame and the chassis is provided which is stiff enough for all power transmission purposes, but is arranged to yield to undue 60 strains and movements in the chassis, so as to prevent injury to or breakage of the motor or motor-frame or parts.

The invention will be further readily understood from the following description and 65 claims, and from the drawings, in which latter:

Figure 1 is a plan view of my improved device, as applied to a motor truck, the chassis being partly broken away and partly in 70 section.

Fig. 2 is a side elevation of the same.

Fig. 3 is a front end view of my improved device, the motor-frame being partly broken away, and the chassis shown in section on 75 the line 3—3 of Fig. 1.

Fig. 4 is a plan view detail of the same, the chassis being shown in section on the line 4—4 of Fig. 3.

Fig. 5 is a detail of the same in vertical 80 section, taken on the line 5—5 of Fig. 3.

Fig. 6 is a rear end view of my improved device, the chassis being shown in section on the line 6—6 of Fig. 1.

Fig. 7 is a perspective view of one of the 85 spring supports.

Fig. 8 is a plan view detail, partly in section, showing the connection of the spring support with the motor and the chassis.

Fig. 9 is a vertical section of the same, 90 taken on the line 9—9 of Fig. 8; and,

Fig. 10 is a vertical section of the same, taken on the line 10—10 of Fig. 8.

The chassis is represented at 11, and in the present exemplification comprises side 95 I-beams 12 and end cross-girts 13, 14, suitably bolted or riveted together at the corners, for forming as rigid a structure as possible. The chassis may, if desired, be provided with suitable cross-braces or diagonal braces as is usual in constructions of this nature.

The motor is exemplified at 18, and may be a motor of any suitable construction, being shown as an internal combustion 105 motor, having its crank-shaft 19 extending lengthwise of the chassis.

The mounting of the motor on the chassis is shown as a three-point suspension mounting, comprising a pivotal mounting at one 110 end of the motor and a resilient mounting at each side of the other end of the motor.

Thus one end of the motor, represented as the front end, is hung from a pivot-stud 21 received in bearings 22 of lugs 23 extending from the motor frame. The pivot is located 5 intermediate of the sides of the motor-frame. The pivot is also received through a bearing 24 in a cross-beam 25. This cross-beam has bearings 26 at its respective ends. A pivot-bolt 27 is received through the bearing 26 at 10 each end of the cross-beam and a bearing 28 in a bracket 29, one of these brackets being located at each end of the cross-beam, the brackets at the respective sides of the chassis being secured to the side beams thereof, as by 15 bolts 30 and nuts 31. A nut 32 also coacts with each of the bolts 27 for firmly holding together the bearings 26, 28. Suitable nut-locking or clamping means may be provided.

The other end of the motor-frame is at 20 each side thereof connected with the chassis by resilient means, exemplified as a leaf-spring 36, which forms a firm but resiliently yieldable connection between the motor and the chassis, the connection being sufficiently 25 firm for all power transmission purposes, but resiliently yieldable to accommodate undue strains and movements in the chassis in order to avoid damage and breakage which might be due to unyielding connections between the same, such unyielding connections 30 having heretofore resulted in damage and breakage to the motor and its parts.

The leaf-springs are preferably of heavy vanadium spring steel. They are preferably 35 bent in form with their edges presented up and down. They are shown of substantially U-shape, comprising limbs 37 and 38. The open ends of the bent leaf-springs are preferably presented in the direction of length 40 of the chassis. The limbs 37 are shown secured to the side I-beams 12 at the respective sides of the chassis, the limbs 38 being secured to the motor-frame.

The limbs 37 are preferably secured in 45 rigid manner to the chassis. Thus a bolt 39 passes through a hole 40 in the spring and a hole 41 in the I-beam, a nut 42 clamping the parts in place, and a bolt 43 passes through a slot 44 in the limb 37 and a hole 50 45 in the chassis, a nut 46 clamping the parts in place. The slot is provided to permit adjustment of the spring with relation to the chassis and the motor-frame, using the bolt 39 as a pivot during adjustment so as to provide relative adjusting means between the 55 motor and the chassis when mounting the motor in the chassis.

A bolt 51 is received through a hole 52 in the limb 37, and a hole 53 in the limb 38, and 60 is threaded into a threaded hole 54 in the motor-frame, the hole 52 being provided merely for the purpose of permitting the headed bolt, which is a substantially long bolt, to be received in the hole 53 and into 65 the motor-frame. The construction con-

templates the attachment of the springs to the motor-frame prior to the attachment of the same to the chassis.

The motor is provided with a rib 56 at each side thereof, above the respective limbs 70 38 of the spring, each of the ribs, however, being spaced from the limb 38 by a space 57. The ribs are preferably not intended to act as normal supports for the motor on the springs, but merely as safety members to 75 prevent dropping of the motor in case the bolts 51, or either of the same, which secure the springs to the motor-frame, should break, shear off, or become loose. The mountings of the motor-frame on the springs 80 are preferably pivotal mountings, pivotal yield at the respective sides of that end of the motor-frame being permitted relatively to the chassis on the respective bolts 51.

The motor is supported firmly for all 85 power transmission purposes. In case there should be torsional movement of the chassis, caused, for instance, by the raising or dropping of one corner, relative movement between the chassis and the motor-frame is 90 permitted by the resilient yieldable substantially stiff supporting springs 36. The pivotal connections at the forward end of the motor, in the present exemplification, also compensate for such resiliently yield- 95 ing movements. In case of opposite length-wise strains or movements at the respective sides of the chassis, the spring-supports 36 are permitted to compensate for such strains or movements by yielding in the springs, the 100 pivotal connections of the cross-beam 25 with the chassis and the motor-frame aiding in compensating for such strains and movements.

The spring mountings permit resilient 105 yielding in the direction of length of the chassis and in directions perpendicular to the plane of said chassis, the pivotal mountings of the motor-frame being complementary to and aiding in such movements.

While I have shown the spring-supports at only one end of the motor, and have shown one at each side of said end, it is obvious that the number of spring-supports may be changed, and that other changes in construction may be made, without departing from my invention within the scope of the appended claims.

Having thus fully described my invention, what I claim as new and desire to secure by 120 Letters Patent, is:

1. In a self-propelled vehicle, the combination of a chassis, a motor for propelling the vehicle, and means for mounting said motor on said chassis comprising a bent 125 leaf-spring the edges of which are presented up and down and the respective limbs whereof are secured respectively to said chassis and to said motor.

2. In a self-propelled vehicle, the combi- 130

nation of a chassis, a motor for propelling the vehicle, and means for mounting said motor on said chassis comprising a bent leaf-spring the edges of which are presented up and down, and means for securing the respective limbs of the latter to said chassis and to said motor, said last-named means including a pivot-connection.

3. In a self-propelled vehicle, the combination of a chassis, a motor for propelling the vehicle, pivot-means for connecting one end of said motor intermediate of its sides to said chassis, and a bent leaf-spring having its edges presented up and down for connecting each side of said motor with said chassis at the other end of said motor.

4. In a self-propelled vehicle, the combination of a chassis, a motor for propelling the vehicle, pivot-means connecting one end of said motor to said chassis comprising a cross-beam, a pivot-connection between said motor and said cross-beam having a pivotal axis extending longitudinally of said chassis, and a pivot-connection between each end of said cross-beam and said chassis, said last-named pivot-connections having pivotal axes substantially perpendicular to the plane of said chassis, and resilient means connecting the other end of said motor to said chassis.

30 said last-named means comprising a bent substantially stiff leaf-spring between each side of said motor and said chassis, said bent substantially stiff leaf-springs having their open ends projected in the direction of length of said chassis, and means for securing the limbs of said leaf-springs respectively to said motor and to said chassis.

5. In a self-propelled vehicle, the combination of a chassis, a motor for propelling the vehicle, pivot-means connecting one end of said motor to said chassis comprising a cross-beam, a pivot-connection between said motor and said cross-beam having a pivotal axis extending longitudinally of said chassis, and a pivot-connection between each end of said cross-beam and said chassis, said last-named pivot-connections having pivotal axes substantially perpendicular to the plane of said chassis, and resilient means connecting the other end of said motor to said chassis, said last-named means comprising a bent

substantially stiff leaf-spring between each side of said motor and said chassis, said bent substantially stiff leaf-springs having their open ends projected in the direction of length of said chassis, and means for securing the limbs of said leaf-springs respectively to said motor and to said chassis, said last-named means including a pivot-connection for each of said leaf-springs.

6. In a self-propelled vehicle, the combination of a chassis, a motor for propelling the vehicle, and means for mounting said motor on said chassis comprising a substantially stiff bent leaf-spring the edges of which are presented up and down, means for securing one of the limbs of said leaf-spring to said chassis, and pivot-means for securing the other limb of said leaf-spring to said motor, said motor provided with a projection extending above but spaced from said last-named limb.

7. In a self-propelled vehicle, the combination of a chassis, a motor for propelling the vehicle, and means for mounting said motor on said chassis comprising a substantially stiff substantially U-shaped leaf-spring having its edges presented up and down, means for adjustably securing one of the limbs of said leaf-spring to said chassis, and pivot-means for connecting the other limb of said leaf-spring to said motor.

8. In a self-propelled vehicle, the combination of a chassis, a motor for propelling the vehicle, and means for mounting said motor on said chassis comprising a substantially stiff substantially U-shaped leaf-spring having its edges presented up and down, means for adjustably securing one of the limbs of said leaf-spring to said chassis, and pivot means for connecting the other limb of said leaf-spring to said motor, said motor provided with a projection extending over said last-named limb.

In testimony whereof I have hereunto signed my name in the presence of two subscribing witnesses.

OTTO ARMLEDER.
